UNITED STATES PATENT OFFICE

138,160

DESIGN FOR A MARBLE GAME BOARD

Carl G. Lins, Tuckahoe, N. Y., assignor of one-half to Stuart R. Wallcott, Tuckahoe, N. Y.

Application April 12, 1944, Serial No. 113,232

Term of patent 14 years

(Cl. D34—5)

To all whom it may concern:

Be it known that I, Carl G. Lins, a citizen of the United States, and a resident of Tuckahoe, in the county of Westchester and State of New York, have invented the new, original, and ornamental Design for a Marble Game Board, of which the following is a specification, reference being had to the accompanying drawing, forming part thereof, in which—

Figure 1 is a plan view of a marble game board embodying my invention;

Fig. 2 is an end view thereof.

I claim:

The ornamental design for a marble game board, as shown.

CARL G. LINS.
